UNITED STATES PATENT OFFICE.

SIDNEY V. JAMES, DECEASED, LATE OF NIAGARA FALLS, NEW YORK, BY SIDNEY C. JAMES, ADMINISTRATOR, OF BUFFALO, NEW YORK, ASSIGNOR TO WM. A. ROGERS, LIMITED, OF TORONTO, CANADA, A CORPORATION OF ONTARIO, CANADA.

DESIGN FOR A SPOON OR SIMILAR ARTICLE.

Application filed April 2, 1928. Serial No. 26,098. Term of patent 7 years.

To all whom it may concern:

Be it known that SIDNEY V. JAMES, deceased, late a citizen of the United States and resident of Niagara Falls, in the county of Niagara and State of New York, has invented a new, original, and ornamental Design for a Spoon or Similar Article, of which the following is a specification, reference being had to the accompanying drawing forming a part thereof, wherein:

spoon or similar article, showing the new design;

Figure 2 is a reverse view of the same; and Figure 3 is a section on the line 3—3 of Fig 1.

What is claimed is:

The ornamental design for a spoon or similar article, as shown.

SIDNEY C. JAMES,
Administrator of the Estate of Sidney V. James, Deceased.
